(57) **CLAIM**

The ornamental design for a swirl spindle, as shown and described.

DESCRIPTION

FIG. 1 is a perspective view of a swirl spindle of the present invention with a bracket and a hook at opposite ends thereof broken away, shown in phantom and forming no part of the invention;

FIG. 2 is a side elevational view of the swirl spindle;

FIG. 3 is an opposite side elevational view of the swirl spindle;

FIG. 4 is a front elevational view of the swirl spindle;

FIG. 5 is a rear elevational view of the swirl spindle;

FIG. 6 is a top plan view of the swirl spindle; and,

FIG. 7 is a bottom plan view of the swirl spindle.

It is understood that the broken lines also shown in FIGS. 2-5 are for illustrative purposes only and form no part of the claimed design.
